UNITED STATES PATENT OFFICE.

FRANKLIN LUTZ, OF ADA, OHIO, ASSIGNOR OF ONE-HALF TO W. J. SCHWENCK, OF BUCYRUS, OHIO.

TRACE-EYE.

1,131,397.

Specification of Letters Patent.

Patented Mar. 9, 1915.

Application filed October 4, 1913. Serial No. 793,434.

To all whom it may concern:

Be it known that I, FRANKLIN LUTZ, a citizen of the United States, residing at Ada, in the county of Hardin, State of Ohio, have 5 invented certain new and useful Improvements in Trace-Eyes; and I do hereby declare the following to be a full, clear, and exact description of the invention, such as will enable others skilled in the art to which 10 it appertains to make and use the same.

This invention relates to improvements in traces for harness, and particularly to the swingletree receiving eye therefor.

The principal object of the invention is to 15 provide a simple reinforcing means to protect the eye against wear.

Other objects and advantages, will be apparent from the following description, when taken in connection with the accompanying 20 drawings.

In the drawings: Figure 1 is a side elevation of a trace. Fig. 2 is a vertical transverse sectional view on the line 2—2 of Fig. 1. Fig. 3 is a horizontal longitudinal sectional view on the line 3—3 of Fig. 1. Fig. 25 4 is a perspective view of the reinforcing member removed.

Referring particularly to the accompanying drawings, 10 represents the end of the trace, which is formed of two plies or layers. Formed transversely through the layers are the registering openings 11, the reinforcement and protection of which is the principal object of the present invention. Disposed between the layers are two metallic reinforcing eyelets which consist of the centrally enlarged and transversely apertured portions 12 and the oppositely extending apertured ears 13. Extending from one side 30 of the member is a tubular portion 14, the bore of this portion registering with the

opening of the plate. There are two of these plates for each opening of the trace strap, these plates being placed back to back so that the tubular portions extend from opposite sides. The plates thus placed are then disposed between the layers of the trace so that the tubular portions 14 project into the openings of the layers. Rivets 15 are then passed through the layers of the trace and through 45 the openings of the ears 13 to firmly clamp the eyelets in place. The usual line of stitching is then sewed around the edges of the layers of the trace, thus securely holding the layers closely together with the tubular 50 members 14 disposed in the opening.

From the foregoing, it will thus be seen that I have provided a simple and cheap reinforcing device for a trace eye, and one which can be quickly and easily replaced by 55 simply cutting the stitches of the layers.

What is claimed is:—

The combination with a horizontally split trace end, of a reinforcing device for the trace eye secured within the trace and comprising a pair of plates having apertured 60 ears and a centrally enlarged apertured portion, and a laterally extending open ended tubular portion secured to the plate at the edge of the said opening, said plates being 65 arranged back to back between the layers of the trace end with the tubular members extending into the openings of the said layers, and the ears in registry, and fastening devices disposed through the layers and the 70 registered ears.

In testimony whereof, I affix my signature, in the presence of two witnesses.

FRANKLIN LUTZ.
